CLAIM

The ornamental design for a set of panels for window blinds, awnings, and room dividers, as shown and described.

DESCRIPTION

FIG. 1 is a front elevational view of a set of panels for window blinds, awnings, and room dividers, the rear being identical, showing our new design;

FIG. 2 is a side elevational view, the opposite side being a mirror image thereof; and,

FIG. 3 is a top plan view, the bottom view being identical thereof.
